THEODORE L. EGNOV, OF HILLSIDE, NEW JERSEY

RUBBER ROLLER POLISHING MACHINE

Application filed September 5, 1930. Serial No. 479,864.

The present invention relates to an improved roller polishing machine, and more particularly to a machine for polishing composition rollers such, for instance, as are used for inking purposes in printing presses, said polishing operations being performed after the surface of the roller has been ground. An object of the invention is to provide such a machine in which rollers of various lengths and diameters may be polished, and which will impart a uniformly polished surface thereto. Another object is to provide a machine which will be automatic in operation, the carriage of the polishing element being automatically fed from one end of the roller to the other as the roller is rotated.

A further object is to provide an improved polishing element, which will engage the roller under any desired tension, and in which the polishing surface may be readily renewed as it becomes worn.

With the above and other objects in view an embodiment of the invention is shown in the accompanying drawings and this embodiment will be hereinafter more fully described with reference thereto, and the invention will be finally pointed out in the claims.

In the drawings:

Fig. 1 is a front elevation of the roller polishing machine, according to the present embodiment of the invention.

Fig. 2 is an end view thereof.

Fig. 3 is an enlarged end view of one of the adjustable roller supports, the adjacent portion of the frame being shown in cross-section.

Fig. 4 is a detail front view of one of the guide rail supports.

Fig. 5 is a side view thereof, showing the rails in cross-section.

Fig. 6 is an enlarged front elevation of the polishing element carriage, and showing the adjacent supporting and feeding parts of the machine.

Fig. 7 is a plan view, with certain parts broken away, of the polishing element.

Fig. 8 is a vertical sectional view, enlarged, taken along the line 8-8 of Fig. 1.

Fig. 9 is a detail view of the feed clutch mechanism for the polishing element car-

riage, and showing the same in one operative position.

Fig. 10 is a similar view, and showing the same in another operative position.

Similar reference characters indicate corresponding parts throughout the several figures of the drawings.

Referring to the drawings, the machine, according to the present embodiment of the invention comprises a pair of spaced table supports 10 and 11 supporting the ends of the polishing mechanism, the table 11 carrying at its under side a driving motor 12 and a worm gearing 13 driven thereby. The shaft of the motor is provided with a pulley 14 for driving the work carrying spindle, presently to be described, and the worm gearing is provided with a sprocket gear 15 for driving the feed mechanism.

Upon the table supports 10 and 11 there are respectively mounted standards 16 and 17, having flanges 18 at their front and rear edges and between these supports a pair of longitudinal angle iron rails 19 and 20 are mounted, being secured to the supports by bolts 21, as shown in Fig. 3. The rails 19 and 20 form a longitudinal channel within which the supports for the work carrying spindle are adjustably mounted. These supports comprise a relatively long base 22, slidably engaged with the rails 19 and 20, an upright portion 23 having a pillar block 24 mounted in an opening 25 in its upper portion, and a locking plate 26 secured to the rearward side of the portion 23 and projecting downwardly at the rearward side of the rail 20 where it is provided with a set screw 27 for binding against the rail and securing the position of the support.

The ends of the spindle 28 carrying the roll 29, to be polished, are mounted in the pillar blocks 24 of the supports at each end. At one end the spindle is connected by a chuck 30 and a longitudinally adjustable coupling 31 to a counter drive shaft 32 mounted in bearings 33 and 34 supported upon the table support 11, said shaft being provided between the bearings with a pulley 35 connected by a belt 36 to the drive pulley 14 of the motor 12. With this arrangement rolls of

any desired length may be mounted in the machine.

A pair of standards 37 and 38 are respectively mounted on the table supports 10 and 11, and support between them a series of rails for slidably mounting the polishing element carriage and feed mechanism, and comprising a relatively wide carriage supporting rail 39 secured at its ends in suitable recesses to the rearward sides of said standards, relatively narrow vertically aligned and spaced feed chain supporting rails 40, 41 and 42 secured at their ends in suitable recesses in the forward sides of said standards, and a forwardly disposed cam carrying rail 43 also secured at its ends in suitable recesses in the forward sides of said standards and arranged between the rails 40 and 41.

The standards 37 and 38 also respectively carry journal bearings 44 and 45, in which are journaled shafts 46 and 47 having sprocket gears 48 and 49 secured upon their forward ends, and over which an endless feed chain 50 passes, the upper portion of the chain between the rollers being supported on the rail 40 while the lower portion moves in the slot between the rails 41 and 42, being supported on the rail 42. For the purpose of continuously driving the sprocket chain in the direction indicated by the arrows a gear 51 is secured upon the rearward end of the shaft 47, and is driven by a sprocket chain 52 extending from the sprocket gear 15 of the worm gearing 13. Every other link of the sprocket chain is provided with an outwardly projected extension 53, and which is adapted to cooperate with the carriage of the polishing mechanism, and as will presently more fully appear.

The polishing element carriage frame 54 is vertically disposed and is provided at its upper portion adjacent its ends with flanged rollers 55 and 56 which ride upon the upper side of the rail 39; another flanged roller 57 being provided at the mid-portion of the frame which engages the lower side of said rail 39.

Upon the rail 43 are adjustably mounted two flanged cam plates 58 and 59 secured in adjusted position by set-screws 60 and 61, and respectively provided with inclined cam surfaces 62 and 63, the surface 62 facing downwardly and the surface 63 facing upwardly, their inclination being in the same direction. These cam surfaces are disposed in relation to be engaged by a roller 64 carried upon a yoke 65 slidably mounted on a vertically disposed rod 66 that is slidably mounted in bearings 67 and 68 formed as a part of the carriage frame. A second roller 69 is secured at the back of the yoke 65 and rides in a vertically disposed slot 70 of the carriage frame, serving to hold the yoke in alignment and prevent it from turning upon the rod 66.

The yoke is provided upon each end portion

with a projection 71, the upper projection being arranged to engage the cam surface 72 of a latch 73 pivotally connected at 74 to the carriage frame, and provided with a spring 75 which normally holds it in engagement with a roller support 76 secured upon the vertically movable rod 66. The roller support 76 carries a roller 77 adapted for engagement with the extensions 53 of the upper traverse of the feed chain as said roller is moved into the path of said extensions. The roller support is provided with a rearwardly projected end portion 78 that bears upon the face of the carriage frame to prevent the roller support and rod 66 from turning. The latch 73 is further provided with a detent tooth 79 for engagement with the top edge portion of the roller support when the latter is in its lowered position, as indicated in Figs. 1, 6, 8 and 9.

The lower projection 71 of the yoke is adapted to engage the cam surface 72 of a lower latch 73 disposed in reverse relation to the upper latch and in the same relation to a lower roller support 76, the roller 77 of which is adapted to engage the extensions of the lower traverse of the feed chain in the upper position of the yoke, as indicated in Fig. 10.

Compression springs 80 are respectively positioned upon the rod 66 between each of the roller supports and the yoke 61 and upon release by the latches project the roller supports in one direction or the other.

The operation of the feed mechanism is as follows. During feed of the carriage to the right, Fig. 6, the upper roller 77 is in engagement with the extensions of the feed chain and the yoke 65 is in its lowered position. As the roller 65 of the yoke comes into engagement with the cam surfaces 63 the yoke is forced upwardly on the rod 66, compressing the upper spring 80, and as the upward movement of the yoke continues the upper projection 71 engages the cam surface 72 of the latch 73 swinging it outwardly to release the detent tooth 79 from the upper roller support, whereupon the compressed upper spring 80 projects the rod 66 and the upper and lower roller supports carried thereby upwardly, thus disengaging the upper roller 77 from the upper right-feed traverse of the feed chain and engaging the lower roller 77 with the lower left-feed traverse. The rod and roller supports are retained in this upper position, Fig. 10, through engagement of the tooth 79 of the lower latch 73 with the lower roller support. At the end of the movement to the left the roller 64 engages the cam surface 62, compressing the lower spring 80 and releasing the lower latch to shift the parts to the lower or right-feed position, the upper roller 77 being engaged with the upper traverse of the feed chain, and the lower roller 77 being disengaged from the lower traverse. Obviously the points of reversal of the feed may

be changed as desired, merely by adjusting the positions of the cam plates 58 and 59.

In addition to the rollers 55, 56 and 57 which support the carriage frame on the rail 39, the frame is provided with an upper horizontally arranged roller 81 above the roller 57, and lower horizontally arranged rollers 82 and 83 below the rollers 55 and 56, and which engage the front surface of the rail 39 for the purpose of equalizing the support of the frame and reducing vibration.

The polishing element is carried by a frame comprising a pair of side plates 84 connected by transverse bars 85, 86 and 87, and mounted for swinging movement upon a shaft 88 journaled in bearings 89 and 90 formed upon the upper portion of the carriage frame. The bars 85 and 86 are arranged adjacent the inner and outer ends of the frame at each end of cut-outs 91 in the side plates, and have connected thereto the ends of a series of cushioning coil-springs 92, which back up a pad 93 having its reduced inner and outer ends secured to the under sides of the bars 85 and 86 by means of retaining strips 94 and 95 screwed to said bars. This pad, it will be observed, rests upon the roller to be polished, and for the purpose of imparting the desired pressure thereto a rod 96 is pivotally mounted upon a shaft 97 secured between the side plates, a weight 98 being removably secured thereon. Obviously different sized weights may be readily secured upon the rod 96 to vary the pressure.

An abrasive polishing strip 99 is carried across the face of the pad 93, and for the purpose of readily renewing this strip as it becomes worn the same is supplied from a roll 100 mounted on a shaft 101 supported in the frame, said strip being carried over a roller 102 adjacent the bar 85 and secured at its end between the bar 87 and a retaining bar 103 secured by wing nuts 104. By loosening the wing nuts the strip may be pulled forwardly to bring a new surface into place, the surplus being torn off.

In order to prevent loosening of the strip a tension device 105 is provided on the shaft 101, which normally holds the roll against rotation, and which may be released when it is desired to renew the strip.

By the use of a variable speed motor for operating the machine, the speed of the roller 29 and the travel of the connected feed chain 50 may be automatically changed in a like manner, and in instances where it is desirable to change the speed of the roller with respect to the travel of the chain, it can be accomplished by substituting a larger or smaller sprocket for the sprocket 15 and the sprocket on the shaft 47 driven thereby.

I have illustrated and described a preferred and satisfactory embodiment of the invention, but it will be obvious that changes may be made therein, within the spirit and

scope thereof, as defined in the appended claims.

Having thus described my invention what I claim and desire to secure by Letters Patent is:—

1. In a machine for polishing rollers, a roller carrying spindle, a carriage movable longitudinally of the roller carried by said spindle, a polishing element carried by and movable with said carriage and comprising a frame including spaced-apart side plates hinged to said carriage, transverse bars connecting said plates, a relatively flat pad having its opposite edge portions secured to said transverse bars, a roll of polishing material carried by the frame, a portion of said material extending across the face of the pad for contact with said roller, and an adjustable plate beneath which said material is drawn from said roll to bring new portions into roller engaging relation.

2. In a machine for polishing rollers, a roller carrying spindle, a carriage movable longitudinally of the roller carried by said spindle, a polishing element carried by and movable with said carriage and comprising a frame hinged to said carriage and extending above said roller, a relatively flat pad having its opposite edge portions secured to spaced-apart members of the frame, a series of springs extended across the underside of the pad to stiffen and support the same, a roll of polishing material carried by the frame, a portion of said material extending across the face of the pad for contact with said roller, and an adjustable plate beneath which said material is drawn from said roll to bring new portions into roller engaging relation.

3. A machine for polishing rollers comprising a frame including a longitudinal guide rail and a cam-carrying rail, cams adjustably mounted on the cam rail, a carriage for the polishing element including in part a vertical plate having a guide slot therein, an endless feed chain having radial extensions, a vertically movable rod mounted on the frame plate, a yoke slidably mounted upon the rod and carrying oppositely projected rollers one to be guided in the slot and the other to be engaged and operated by the cams, springs to normally retain the yoke in an intermediate position, a roller support slidably mounted on each end portion of the rod in engagement with the said springs, and each carrying a roller adapted to engage the before mentioned radial extensions of the endless feed chain, spring actuated latches mounted upon the side plate adapted to engage the said roller supports and alternately hold them, this spring and yoke, first in one position and then in another for engagement by the extensions of the chain and whereby the carriage may be automatically moved.

from one end of the machine frame to the other.

4. A machine for polishing rollers comprising a frame including a longitudinal guide rail and a cam-carrying rail, cams adjustably mounted on the cam rail, a roller carrying spindle, a carriage, a polishing element carried thereby including in part a vertical plate having a guide slot therein, an endless feed chain, a vertically movable rod mounted on the plate, springs mounted upon the rod, a roller support mounted on each end portion of the rod in engagement with the said springs, a roller on each support adapted to engage the before mentioned endless chain, spring actuated latches mounted upon the side plate adapted to engage the said roller supports, means movable relatively to said vertically movable rod, adapted upon movement in one direction to first compress one of said springs and thereupon release one of said latches and upon movement in the opposite direction to first compress said other spring and thereupon release said other latch, and cam means for causing the movement of said latches at predetermined points.

5. A machine for polishing rollers comprising a frame including longitudinal guide rail feed chain supporting rails, and a cam-carrying rail, cams adjustably mounted on the cam rail, a roller-carrying spindle, a polishing element, a carriage for the polishing element having a vertical slot, an endless feed chain mounted to operate beside said chain supporting rail and having engaging means, a yoke slidably mounted upon the rod and carrying oppositely projected rolls one to be guided in the vertical slot and the other to be operated by the cams, springs to normally retain the yoke in an intermediate position, a roller support mounted on each end portion of the rod in engagement with the said springs, and each carrying a roller adapted to be engaged by the before mentioned endless chain, spring actuated latches mounted upon the carriage adapted to engage the said roller supports and alternately hold them, the spring and yoke, in one position and then in another for engagement by the chain and whereby the carriage may be automatically moved from one end of the machine frame to the other.

6. A machine for polishing rollers comprising a frame including a longitudinal supporting guide rail feed chain supporting rails and a cam-carrying rail, a roller-carrying spindle, a polishing element, a carriage for said polishing element having wheels to engage the guide rail, and endless feed chain having recesses, vertically movable means carried by said carriage adapted in one position to operatively connect said carriage to the upper transverse of said chain and in another position to operatively connect said car-

riage to the lower transverse including a pair of releasable latches mounted on the carriage for respectively retaining said vertically movable means in one position or the other, a pair of spring means adapted to respectively impart movement to said vertically movable means upon release by one or the other of said releasable latches, means movable on said vertically movable means adapted upon movement in one direction to first compress one of said spring means and thereupon release one of said releasable means and upon movement in the opposite direction to first compress said other spring means and thereupon release said other releasable means, and means for causing the movement of said last named means at predetermined points.

Signed at Bridgeport in the county of Fairfield and State of Connecticut this 3rd day of Sept. A. D. 1930.
